UNITED STATES PATENT OFFICE.

JAMES C. OLLARD, OF TACOMA, WASHINGTON.

CLUTCH.

1,333,440.

Specification of Letters Patent.

Patented Mar. 9, 1920.

Application filed January 18, 1917, Serial No. 143,075. Renewed October 31, 1919. Serial No. 334,886.

To all whom it may concern:

Be it known that I, JAMES C. OLLARD, a citizen of the United States, residing at Tacoma, in the county of Pierce, State of Washington, have invented certain new and useful Improvements in Clutches, of which the following is a specification.

This invention relates to clutching devices whereby a rotating shaft may be releasably connected to another shaft, and has special reference to clutches for use in automobiles, power trucks, tractors, boats, hoisting machines, and in other similar conditions.

This clutch is of the type which runs in oil and in which a single driven disk is engaged between two driving disks.

The objects of this invention are, first, to produce a light and compact mechanism which shall yet be of great strength; second, to provide a means for attaining great leverage on the clamping disks so that a light clutch spring may be used to provide the necessary clamping force; third, to materially reduce the work necessary to release the clamping action of the disks; fourth, to reduce the wear on the control collar; fifth, to provide a means whereby a single adjustment of the mechanism will equally adjust all parts thereof to take up the wear of the friction parts; and sixth, to provide a clutch which can be cheaply made, easily assembled, repaired and adjusted, and which will be effective and efficient in its action.

I attain these and other objects by the devices, mechanisms, and arrangements illustrated in the accompanying drawings, in which—

Figure 1 is a side elevation of the clutch mechanism showing the oil-containing casting in broken lines; Fig. 2 is an end elevation thereof; Fig. 3 is a vertical section of the main body of the clutch; Fig. 4 is an end elevation thereof; Fig. 5 is a vertical section of the clutch assembled and in action; Fig. 6 is a side elevation of the adjustable member of the clutch; Fig. 7 is an end elevation of the movable clutch member; Fig. 8 is an end elevation of the adjustable member, together with the clamp levers mounted thereon, the operating sleeve being shown in cross-section; and Figs. 9, 10 and 11 are respectively a cross-section, longitudinal section, and a plan of a portion of the main body of the clutch illustrating the oil jet device therein.

Similar numerals of reference refer to similar parts throughout the several views.

This clutch is designed to connect a driving shaft with a driven shaft for any of the well known purposes for which such devices are usually used.

Referring to the drawings it will be observed that the driving shaft 1 is provided with a disk or flange 2 at its end. The main body of the clutch is secured to this disk 2 by bolts or other suitable means. This main body consists of a disk portion 3 which is surrounded by a flange portion 4 extending over the clutch mechanism and forming the outer wall of the clutch drum. The disk portion 3 is provided with a small central hole 5 adapted to receive the reduced end 6 of the driven shaft 7, hereinafter described. A series of oiling scoops 8 are formed on the outer surface of the cylindrical flange 4, each such scoop 8 leading to a passage 9 passing through the part 4 as hereinafter more particularly described.

An inner lining casting 10 fits into the cylindrical part 4 of the main body and is provided with an outward flange 11 abutting against the edge of the part 4. Suitable screws 12 pass through the flange 11, into the part 4 to fasten the said lining 10 to the main part. Referring to Fig. 3 it will be seen that the inner edge 13 of the lining 10 is cut away to lighten it, except at six places. At alternate three of these places the lining is formed with an inward-extending shoulder or lug 14, each of which is adapted to be engaged by a suitable arm on the movable clutch member, and at the other three alternate places the lining is formed with a lug 15 from which a dowel pin 16 extends into the wooden friction disk 17. Also said lining 10 is provided, for the purpose hereinafter specified, with three inward-projecting screw-threaded pins 18 positioned near the outer edge, suitable bosses 19 being provided therefor adjacent to said flange 11.

The wooden friction disk 17 is firmly clamped between the inner face of the disk 3 and the six lugs 14 and 15 of the lining 10 by means of the above mentioned screws 12 and is held from any relative rotary motion by means of the three dowel pins 16 which enter suitable holes 20 therein. The wooden friction disk 17 is annular in form, and is concentric with the axis of the shaft 1.

The driven shaft 7 is provided with a reduced end part 6 fitting in the central hole 5 of the disk 3 and with a suitable steel friction disk 21 keyed or otherwise secured thereto, and lying adjacent to the wooden friction disk 17. The end of the shaft 7 is thus partially supported, or rather held in alinement, by the end 6 in the hole 5, but it is mainly supported by a long bearing 22 which in turn is supported by the main body of the clutch as hereinafter described. It is therefore impossible for the shafts 1 and 7 to get out of alinement.

The adjustable member of the clutch is illustrated in Figs. 2, 5, 6 and 8 and consists of a disk portion 23 having a central boss 24 surrounding the shaft 7, said boss 24 having a bearing lining 22 therein, wherein said shaft 7 may turn. The boss 24 is also provided with a keyway 25 therein, which is engaged by a key 26 on the operating sleeve as hereinafter described. The boss 24 is further provided with a screw-nut 27 at its end, said nut being adapted to form a flange against which the clutch spring 28 engages. The disk 23 extends outward from the boss 24 and terminates in a narrow flange 29 which fits in the lining casting 10, and said flange 29 is provided with three lateral extensions 30 each of which is provided with an elongated inclined slot 31 therein, through which the above-described pins 18 pass, said pins being each provided with a suitable nut whereby the flanges 30 are secured to the main body of the clutch. Thus it will be seen that the adjustable member is firmly secured to the main body of the clutch and that the bearing 22, which guides and supports the driven shaft 7, is supported by the said main body and that therefore the shaft 7 and its disk 21 are firmly journaled in the clutch, being free to have rotational and axial relative motion therein so far as these parts are concerned, but held thereby against any relative eccentricity. It is evident that if the adjustable member is slightly turned or rotated within the lining 10, that the pins 18 and the inclined slots 31 will cause the disk 23 to move nearer to or farther from the disks 3 and 17, and that when it has once been thus adjusted it is held in such adjusted position by means of the nuts on the pins 18. The disk 23 is provided with three holes 32 (Fig. 5) therein and adjacent each such hole is also provided with a pair of lugs 33 extending therefrom wherein the clutch levers are mounted, a portion of each such lever passing through the hole 32. Thus it will be seen that the parts 3, 4, 10 and 23 form a substantially closed drum wherein the clutching disks are mounted. Another central boss or hub 34 extends from the inward face of the disk 23 and is adapted to support and guide the movable clutch member.

The movable clutch member (Figs. 5 and 7) is formed of a metal disk 35 slidably mounted on the boss 34 and having outwardly extending lugs or arms 36 which embrace and engage the shoulder lugs 14 formed on the lining 10 and whereby it is forced to rotate with the main body of the clutch though free to move axially therein. An annular wooden disk 37 is secured to the face of the disk 35, adjacent to the steel disk 21 of the shaft 7, by means of suitable bolts. A ring 38 of steel or other suitable metal, is secured to the opposite or outer face of the disk 35, said ring 38 being concentric with the clutch and being adapted to be engaged by those portions of the clutch levers which pass through the holes 32 in the adjustable disk 23.

The clutch levers each consist of an arm 39 pivotally secured at one end by means of the pivot pin 40 to the pair of lugs 33 on the disk 23, and each has a head 41 formed at the other end, said heads 41 lying between and engaging the lugs 42 formed on the operating sleeve. A short arm 43 extends from the arm 39 at a point close to the pivot pin 40 and passes through the hole 32 in the disk 23. A hardened steel shoe 44 is removably secured to the end of the arm 43 and bears on the steel ring 38 on the movable clutch disk 35, as above described. Figs. 2 and 8 clearly show that the arms 39 are not arranged radially but are turned so that their heads 41 lie adjacent the operating sleeve 45 and the portions of the arms 39 near the said heads 41 are practically tangent to the surface of the sleeve, thus securing a much greater leverage than could be secured by any radial arrangement of the arms in the limits of the practical size of the clutch drum. The portion of the lever 39 between the head 41 and the straight substantial tangentially arranged portion, is curved approximately concentric with the sleeve.

The operating sleeve 45 fits over the central boss 24 of the adjustable member and is connected thereto by means of the key 26 on the sleeve which slides in the keyway 25 in the boss 24 so as to be free to move axially thereon but having no relative rotary motion allowed. The sleeve is provided with a cylindrical extension 46, of larger diameter and forming a casing over the clutch spring 28 which bears against the nut 27 as above described and against the shoulder 115 formed between the parts 45 and 46. The extension 46 is provided with a flange 47 around its outer face intermediate of its ends and with a nut 48 at its outer end. The usual operating collar 49, provided with 120 trunnions 50, is mounted between a pair of antifriction rings 51, said parts 49 and 51 being mounted on the extension 46 between the flange 47 and the nut 48. The sleeve 45 is also provided with three pairs of lugs 42 130

(Figs. 2, 5 and 8) which are positioned as clearly shown in Fig. 8 so that the head 41 lying between the lugs forming a pair will be positioned on a radius substantially at right angles to the radius leading to the pivot 40. The key 26 prevents the relative rotational movement of the arm and the lugs so that, in whatever position the adjustable member may be turned in making the above described adjustment, the sleeve and the lugs 42 move with it and with the arm 39 mounted on it so that the heads 41 always remain between the lugs 42.

In view of the fact that by arranging the arms 39 so that they lie in a non-radial direction and can therefore have a great leverage, it is evident that a smaller pressure is required to produce the same clamping effect than would be the case if they were radial and had a smaller leverage. Thus the strength of the clamping spring 28 may be correspondingly reduced and this reduction in the compression of the spring 28 has two very practical advantages. By referring to Fig. 1 it will be seen that the foot-lever 52 acts through the two arms 53 to engage the trunnions 50. When the lever 52 is pressed by the foot, it draws the collar 49 and the sleeve 45 outward against the action of the said clutch spring 28 and if this is a stiff spring it is evident that a considerable force must be applied to the foot-lever 52, and when the machine is on a long down-grade this force soon becomes very tiring, hence it is a great advantage to reduce the force of the spring; further, when this withdrawing force is applied to the collar 49, through the trunnions 50 as above, it acts through the ring 51 between it and the nut 48, and, again, if this spring 28 is stiff, the friction between the parts 49, 51 and 48 is quite large and results in a rapid wearing away of the ring 51, while if the spring 28 is weak this wear is very greatly reduced.

It is further to be noted that the wear of all the friction disks 17, 21 and 37 is taken up by the single adjustment of the part 23 in the lining 10, as above described, and is equal at all points around the circle since the part 23 is adjusted as a whole and carries with it all the pivots 40 and their levers 39, hence the adjustment of said part 23 equally adjusts all said pivots and levers and therefore adjusts equally all the shoes 44 and the disk 35.

As above mentioned, the clutch runs in a bath of oil contained in an outer casing indicated by the broken lines 54 in Fig. 1; and the outer surface of the drum or flange 4 is provided with oil scoops 8. Referring to Figs. 9, 10 and 11 it will be seen that the passage 9 leading from the scoop 8 through the part 4 is formed with converging sides so that when the scoop strikes the oil in the bath the inertia of the oil forces it through

the contracted throat of the passage 9 to form a jet squirting the oil into the interior of the clutch against the action both of gravity and centrifugal force and thoroughly and continuously oiling the friction surfaces 70 of the clutch.

Having described my invention, what I claim is:—

1. In a shaft clutch, the combination with a clutch mechanism comprising a driving drum having a clamp disk secured thereto, a movable clamp disk turning with said first disk but axially movable relatively thereto, and a free disk secured to the driven shaft and positioned between said two clamp disks 80 and coaxial therewith and adapted to be clamped therebetween to rotate therewith; of an adjusting member having inclined slots therein; securing bolts in said drum and passing through said slots whereby the axial position of said member is controlled by the relative rotative position of said member and said drum; and clamping means carried by said adjusting member and engaging said movable clamp disk to move it 90 axially, whereby said free disk is clamped between said rotating disks and whereby said clamping action is adjusted by the relative rotation of said adjusting member.

2. In a shaft clutch, the combination with a driving shaft; of a disk having a drum flange formed thereon and secured to said driving shaft, said disk carrying a clamp disk secured to its inner face within the drum; an adjusting member secured to said drum flange and comprising a disk within the drum and an out-turned flange engaging the inner surface of the drum, said adjusting member having inclined slots in said out-turned flange; securing bolts extending inward from said drum and passing through said slots whereby the axial position of said member is controlled by the relative rotative position of said member and said drum, said member closing the 110 drum and having openings, therethrough; a movable clamp disk within the closed drum and adjacent the adjusting member, said movable member turning with said drum but free to move axially therein; a free disk secured to the driven shaft and positioned between said two clamp disks and adapted to be clamped therebetween to rotate therewith; and clamping means carried by said adjusting member and 115 extending through the openings therein to engage said movable clamping disk to move it axially whereby said free disk is clamped between said rotating disks and whereby said clamping action is adjusted by the relative rotation of said adjusting member.

3. In a shaft clutch, the combination with a driving shaft; of a main disk having a drum flange formed thereon; a friction disk positioned adjacent to the inner surface of 130

- said main disk; a lining body fitting in said drum flange and engaging said friction disk to clamp it against said main disk; a flange extending outward from said lining body; and screw means engaging said lining flange and said drum whereby said lining flange is drawn toward said drum flange to clamp said friction disk against said main disk.
- 10 4. In a shaft clutch, the combination with a driving shaft; of a main disk having a drum flange formed thereon; a friction disk positioned adjacent to the inner surface of said main disk; a lining body fitting in said 15 drum flange and engaging the friction disk to clamp it against said main disk; a flange extending outward from said lining body; screw means engaging said lining flange and said drum whereby said lining flange is drawn toward said drum flange to clamp 20 said friction disk against said main disk; and dowel pins extending from the edge of said lining body and extending into suitable holes in said friction disk whereby said 25 friction disk is forced to rotate with said main disk.
5. In a shaft clutch, the combination with a driving shaft; of a main disk having a drum flange formed thereon; an adjusting member comprising a disk within the drum 30 and an out-turned flange fitting in the inner surface of the drum, said adjusting member having inclined slots in its out turned flange, said member closing the drum and having openings therethrough; securing bolts extending inward from said drum and passing 35 through said slots whereby the axial position of said member is adjusted by the relative rotation of said member in said drum; a bearing boss formed on said adjusting 40 member; a driven shaft mounted in said bearing boss; clutch mechanism mounted within the drum whereby said driven shaft is releasably connected to said driving shaft; and clamping means carried by said adjusting member and extending through said 45 openings therein to engage and operate the clutch mechanism, whereby the clamping action between the said two shafts is adjusted by the relative rotation of said adjusting member in said drum.

JAMES C. OLLARD.
